UNITED STATES PATENT OFFICE

136,755

DESIGN FOR A LAMP OR SIMILAR ARTICLE

John Bernard Sindelar, Loyalton, S. Dak.

Application May 25, 1943, Serial No. 110,277

Term of patent 14 years

To all whom it may concern:

Be it known that I, John Bernard Sindelar, a citizen of the United States, residing at Loyalton, in the county of Edmunds and State of South Dakota, have invented a new, original, and ornamental Design for a Lamp or Similar Article, of which the following is a specification, reference being had to the accompanying drawing, form a part thereof.

I claim:

The ornamental design for a lamp or similar article, as shown.

JOHN B. SINDELAR.
